CLAIM

The ornamental design for a smoking accessory, as shown.

DESCRIPTION

FIG. 1 is a rear perspective view of a smoking accessory, showing my new design;

FIG. 2 is a side elevational view of a smoking accessory, showing my new design, the opposite side being a mirror image thereof;

FIG. 3 is a rear elevational view thereof;

FIG. 4 is a plan view thereof;

FIG. 5 is a bottom elevational view thereof;

FIG. 6 is a front elevational view thereof;

FIG. 7 is a front perspective view of the handle of the smoking accessory apart from the body.

FIG. 8 is a plan view thereof;

FIG. 9 is a bottom elevational view thereof;

FIG. 10 is a rear elevational view thereof;

FIG. 11 is side elevational view thereof, the opposite side being a mirror image thereof;

FIG. 12 is a front elevational view thereof; and,

FIG. 13 is a rear perspective view thereof.

The handle and the body of the smoking accessory are shown separately for convenience of illustration.

1 Claim, 4 Drawing Sheets
